UNITED STATES PATENT OFFICE.

ARRIVED E. ROXBERG, OF ROSINGTOWN, MINNESOTA.

HUB-FASTENER.

No. 920,657.

Specification of Letters Patent.

Patented May 4, 1909.

Application filed November 2, 1908. Serial No. 460,621.

To all whom it may concern:

Be it known that I, ARRIVED E. ROXBERG, a citizen of the United States, residing at Ros-
5 ingtown, in the county of Morrison, State of Minnesota, have invented certain new and useful Improvements in Hub-Fasteners; and I do hereby declare the following to be a full, clear, and exact description of the invention, such as will enable others skilled in the art to
10 which it appertains to make and use the same.

This invention relates to devices employed for securing hubs upon axle journals, and has for one of its objects to simplify and im-
15 prove the construction and increase the efficiency and utility of devices of this character.

Another object of the invention is to provide a fastening means wherein the use of screw threads are obviated and the fastening
20 means automatically applied, and removable without the employment of wrenches or other implements.

With these and other objects in view, the invention consists in an axle journal having a
25 cavity in its outer end provided with a reduced communicating aperture, a cap engag-
ing over the outer end of the journal, and spring actuated catch devices swinging from
the cap and operating through the aperture
30 to lock the cap to the journal.

The invention further consists in certain novel features of construction as hereafter shown and described and then specifically pointed out in the claims, and in the drawings illustrative of the preferred embodiment
35 of the invention.

Figure 1 is a longitudinal section of the im-
proved device. Fig. 2 is an end elevation.
Fig. 3 is a section on the line 3—3 of Fig. 1.

40 The improved device may be applied to any of the various forms of axle journals in use, but is more particularly applicable to the journals of the larger class of vehicles, such as farm and freight wagons and the like,
45 and for the purpose of illustration the im-
proved device is shown applied to an axle journal of this class in which 10 represents the skein or shell fitting over the outer end of a wooden axle 11 of the ordinary construc-
50 tion.

The outer end of the skein 10 is provided with a cavity or recess 12, and the skein secured to the wooden axle 11 by a lag screw 13. The recess 12 is formed with a reduced
55 aperture 14 providing communication through the outer end of the skein and where-

by overhanging portions 15 are formed, as shown.

Fitting over the outer end of the skein is a cap 16 preferably with a wrench surface 17. 60 The cap 16 is provided with a central aperture 18 preferably registering with the aperture 14 of the skein and provided with spaced ears 19—20 and extending outwardly from the cap at the sides of the aperture 18. 65

Swinging between the ears 19—20 are two catch members 21—22, the catch members adapted to pass through the aperture 14 and into the recess 12 of the journal when the cap member is positioned upon the jour- 70 nal, the terminals of the catch members having lateral projections 23—24 engaging in the rear of the overhanging portions 15, as shown.

The outer faces of the projections 23—24 75 are oppositely inclined, as shown, so that when the cap is located over the journal the catch members will automatically enter the aperture 14 and extend in the rear of the overhanging portions 15, the catch mem- 80 bers being provided with a spring 25 to maintain them yieldably in their extended position.

A portion of the hub is represented at 26, and the inner face of the cap 16 is designed 85 to bear against the outer face of the hub, while the inner face of the hub bears against the usual collar 27 of the journal. By this simple means it will be obvious that the hub is firmly secured in position upon the jour- 90 nal by simply depressing the cap over the end of the journal with the catch members passing into the recess 12 and their barbed inner ends engaging in the rear of the over-
hanging portions 15, as described. 95

When the nut is to be detached, the catch members 21—22 are compressed by the fingers of the operator or a suitable implement employed for the purpose to withdraw the projections 23—24 from engagement with 100 the overhanging portion 15, when the nut will be free to be detached. To replace the nut it is only necessary to force it inwardly over the outer end of the sleeve, the inclined faces of the projections engaging with the 105 edges of the opening and thereby being automatically compressed and caused to again engage in the rear of the overhanging portions.

The improved device is simple in con- 110 struction, can be inexpensively manufactured, and applied to axle journals of va-

rious sizes, and to axle journals employed upon vehicles of various constructions.

What is claimed, is:—

1. The combination with an axle journal having a cavity in the outer end and with an aperture communicating with the cavity whereby portions of the journal overhang the cavity, a cap bearing over the outer terminal of the journal, and two arms swinging from the cap and extending through the aperture with laterally directed terminals engaging in the rear of the overhanging portions of the journal cavity.
2. The combination with an axle journal having a cavity in the outer end with a reduced aperture communicating with the cavity whereby portions of the journal over-

hang the cavity, a cap bearing over the outer terminal of the journal and provided with an aperture registering with the aperture of the cavity and with spaced ears at the sides of the aperture thereof, two arms swinging between said ears and extending through the apertures with laterally directed terminals in the rear of the overhanging portions of the journal, and a spring operating between said arms.

In testimony whereof, I affix my signature in presence of two witnesses.

ARIVED E. ROXBERG.
